PIPE CLEANER

Filed Jan. 3, 1922

INVENTOR
Fred J. Kehlenbeck,
BY
Wm. H. Campfield,
ATTORNEY.

UNITED STATES PATENT OFFICE.

FRED J. KEHLENBECK, OF NEWARK, NEW JERSEY.

PIPE CLEANER.

Application filed January 3, 1922. Serial No. 526,536.

To all whom it may concern:

Be it known that I, FRED J. KEHLENBECK, a citizen of the United States, and a resident of Newark, county of Essex and State 5 of New Jersey, have invented certain new and useful Improvements in Pipe Cleaners, of which the following is a specification.

This invention relates to a cleaner for smokers' pipes which is adapted for use in 10 different forms so as to fit different forms of bowls of such pipes.

The invention is further designed to provide a cleaner which can be operated by the handle alone to permit an automatic adjustment of its blades to the bowl, or it can be 15 rotated and at the same time spread or contracted manually so as to more positively localize the cleaning.

The invention is illustrated in the accompanying drawing, in which Figure 1 is a side view of the cleaner in a pipe bowl. Figure 2 is an edge view of the cleaner. Figure 3 is a view similar to Figure 1 with the cleaner in a bowl of a different form. Figures 4 and 5 are elevations of the lower 20 part of the cleaner, illustrating the successive steps in cleaning the bowl, and Figure 6 is a perspective view of one of the blades.

The cleaner comprises a suitable handle 10 which, in the form shown, is of substantially flat form and made of two plates 11 and 12 which between them provide a space for the 25 operation of the blades 13. The top part of the handle is provided with an end piece 14, to which the plates 11 and 12 are secured and which assists in spacing the plates apart and also provides a convenient means for grasping the device for turning it.

The blades 13, and for the purpose of 30 illustration I show two opposed blades in the drawing, are arranged so that each of them independently rocks and slides freely on the handle. The blades, on their outer edges 15, are adapted to scrape the inside 35 of the bowl of a pipe to remove incrustations therefrom, and this outer edge is generally formed so as to approximately fit the inner walls of the bowl of a pipe on one side thereof, having the lower outer edge 45 16 around it for this purpose.

To provide for such free rocking and sliding, each of the blades is provided with a slot 17 which extends downwardly and inwardly when the blade is in position. In 50 other words, such slot inclines downwardly

toward the lower end of the other blade, and the pin 18 on each side not only connects and braces the two side plates 11 and 12 of the handle, but these pins pass through the slots and thus act as pivots on which the 60 blades can swing.

Suitable finger-pieces 19 are preferably placed on the top end of each blade.

It will be evident that when the device is to be used, it can ordinarily be used by 65 placing it as shown in Figure 1, which, in the case of heavy incrustations, gradually takes away such interior incrustation or lining in the pipe and cleans it thoroughly, by holding the pipe rigid and turning the cleaner 70 by means of its handle. In the case of a bowl that is larger at the bottom than at the top, as shown in Figure 3, the blades can be made to engage the sides by pressing inwardly on the finger-pieces 19, which 75 spreads the bottom ends of the blades.

Another manner of using the pipe cleaner is shown in Figures 4 and 5, where one blade is advanced materially ahead of the other, and when the handle is turned, the cleaner 80 descends in the pipe, the uppermost blade being gradually worked down into position toward the bottom of the bowl, as the pin of the uppermost blade engages the bottom of the slot of the uppermost blade, which 85 will gradually force the other blade down into the bowl.

It will also be evident that one of the blades can be entirely retreated to its upward limit of movement and the other one 90 advanced, and one of the blades alone used to scrape the inside of the pipe in case of a very small bowl, or if only a portion of the bowl is incrusted.

I claim:

95

1. A pipe cleaner comprising a handle, a pair of blades arranged on opposite sides of said handle, and a connection between each blade and the handle, whereby the blades can freely rock on the handle and also have 100 a longitudinal sliding motion thereon.

2. A pipe cleaner comprising a handle, a pair of blades, each blade having an inwardly inclined slot therein, and means for securing the blades to the handle through the 105 slots.

3. A pipe cleaner comprising a handle, a pair of blades, each blade having an inwardly inclined slot therein, means for securing the blades to the handle through the 110

slots, and finger-pieces on the upper ends of the blades.

4. A pipe cleaner comprising a handle formed of two flat plates spaced apart, blades arranged between the plates and adapted to abut against each other, the blades each having a slot downwardly inclined to-

ward the other blade, and a pin on each side of the handle connecting the plates and passing through a slot in a blade.

10

In testimony that I claim the foregoing, I have hereto set my hand, this 31st day of December, 1921.

FRED J. KEHLENBECK.
